ATTACHMENT FOR TYPEWRITERS

Anna M. Larose, The Pas, Manitoba, Canada

Application October 14, 1940, Serial No. 361,165

1 Claim. (Cl. 197—189)

The present invention relates to attachments for typewriters whereby the user thereof will be able to readily determine at all times the exact unused portion of the paper in the machine.

An important object of the invention is to provide means associated with the platen of a typewriter and rotating therewith for indicating to the operator of the machine the unused portion of the paper in the machine so that he may know well in advance when it will be necessary to remove the paper.

Another object of the invention is to provide an attachment in the form of a cover adapted to be applied to the platen knob, said cover having formed therein or printed thereon suitable indicia for indicating the amount of unused paper remaining at the bottom of the sheet in the machine.

The invention also consists in certain other features of construction and in the combination and arrangement of the several parts, to be hereinafter fully described, illustrated in the accompanying drawing and specifically pointed out in the appended claim.

In describing my invention in detail, reference will be had to the accompanying drawing wherein like characters denote like or corresponding parts throughout the several views, and in which:

Figure 1 is an elevational view of the invention applied to the knob of a typewriter platen.

Figure 2 is a front end view of the attachment.

Figure 3 is a vertical sectional view taken substantially on line 3—3 of Figure 2.

Figure 4 is an elevational view partly in section of a modified form of the invention.

Figure 5 is an elevational view of a still further modified form of the invention.

Referring to the drawing for a more detailed description thereof, the platen of a typewriter is generally designated by the numeral 8, the same being mounted on a shaft 9 to each end of which is attached a wheel or knob 10. The knob 10 usually includes a collar 11 which is secured to the shaft 9 by means of screws or the like 12.

In accordance with the present invention, a cover 13, preferably formed of rubber or similar material, is placed over the knob 10, said cover being preferably cylindrical-shaped to conform to the shape of the knob and of hollow construction as best shown in Figure 3 of the drawing. Integrally formed radially inwardly extending flanges 14 and 15 are provided on each end of the cover and serve to retain the same in position on the knob. It will be observed from an inspection of Figure 3 of the drawing that

the flange 15 flexes inwardly for gripping engagement with the end of the knob.

In the moulding of the cover the area thereof facing the platen 8 is formed with a smooth surface slanting at an angle as indicated at 16, having formed therein or printed thereon suitable indicia designated by the numeral 17. It will be readily observed that the indicia are thus placed in a sheltered area so that they will not be readily eradicated by contact of the fingers with the cover, the indicia serving a purpose to be hereinafter more fully described. The other portion of the cover is formed with substantially V-shaped corrugations 18, certain of the corrugations being more pronounced as indicated at 19, said pronounced corrugations being on a line with the indicia placed upon the area 16. In actual practice, the pronounced corrugations are of various lengths and may be identified by contrasting colors for indicating various turns of the platen.

It will be noted from Figure 1 of the drawing that two lines of numerals are employed with the innermost line indicating the first revolution of the platen roller and the outermost line representing the second revolution of the roller. When initially placing the paper in the typewriter the indicating device is set so that zero is at the starting line with each number representing one inch and it will be readily evident to the user of the machine from the length of paper used whether the platen is on the first, second or third turn. It is generally understood that six lines can be written to the inch and therefore the indicia on the cover are graduated according to inches. Thus when the numeral "1" on the knob has moved into register with the pointer or other indicating means the typist knows that one inch of paper has been moved through the machine. This feature of the device permits the typist to set her typing in a uniform way from the moment the paper is inserted in the machine and to allow uniform spacing at both the top and bottom of the sheet. If, for example, the sheet of paper is 10 inches long and the operator of the machine is interested in determining the space left at the bottom of the sheet only and if a one-inch space is desired at the bottom of the sheet, the operator will remove the sheet when the numeral 9 appears at the chosen starting point. Thus the operator does not have to constantly look at the paper. However, if there is indicated that 8½ inches of the paper has already been fed through the typewriter, the operator will know

that three more lines may be written in order to remove the sheet of paper when the numeral 9 appears on the cover thereby leaving a one-inch space at the bottom. This device is especially important where several sheets of figures are used and when these figures have to be totalled at the bottom of the sheet. If the operator is continuously aware of the length of the paper left he can readily tell at a glance the number of lines he may use before it is necessary to remove the paper.

By permitting the typist to readily and at a glance ascertain either the exact amount of paper that has been fed through the machine or the exact amount remaining in the machine, it is possible for several short forms to be written on a long sheet and the instant device permits the typist to arrange the forms uniformly on the sheet so that they will have even borders after the large sheet has been cut into sections. For instance, four three inch forms may be typed on a twelve inch sheet. The typist knows that the sheet must be cut into three inch lengths after the forms are typed. Thus, if a half inch space is desired at the top of each form, the typist may leave a half inch space by starting one space beyond $\frac{1}{2}$, $3\frac{1}{2}$, $6\frac{1}{2}$ and $9\frac{1}{2}$ points on the platen knob. Upon removing the sheet and cutting the same into three inch sections each form would be found to be uniformly positioned on the sheet and to have uniform borders. When several carbon copies are made, this procedure saves much time in inserting and removing carbons; also, it is frequently difficult to type at the bottom of a sheet and the typist often finds it necessary to hold the sheet with one hand when typing within a half inch from the bottom thereof. This annoying procedure would be avoided three times in the above instance.

The placing of the indicia on the slanting area brings the same in better line of vision on several models of typewriters while maintaining them out of position so that they will not be eradicated by constant contact of the fingers with the cover. The cover being formed of rubber acts as a firm and soft grip that is easily applied to the knob.

In Figure 4 of the drawing, there is shown a modified form of the invention in which the platen knob, which is designated by the numeral 20, is formed with a slanting area 21 on which are placed the indicia 22. A rubber ring 23 is suitably secured on the knob to form a gripping medium. It is, of course, to be understood that the knob 20 will have its periphery cut out for receiving the ring 23. This form of the inven-

tion eliminates the use of a cover since the indicia are applied directly to the knob.

In Figure 5 of the drawing there is shown a still further modified form of the invention in which the rubber ring 23 has been dispensed with and in place thereof the knob has been formed with corrugations 24 similar to the corrugations formed in the rubber cover and with certain of the corrugations more pronounced, as indicated at 25, in line with the indicia 26. The indicia 26 are on an area similar to the forms previously described and the method of determining the unused portion of the paper in the machine is the same as described in connection with the preferred form.

Any form of the invention above described and illustrated in the drawing will indicate the position of a typing sheet at all times thereby enabling the operator of the machine to have the lines of typing evenly distributed on the sheet which is especially desirable when compiling a several page report, manuscript and the like. Each page will have the first and last lines of typing equally spaced from the top and bottom edges thereof.

Also it will be understood, of course, by those skilled in the art that variations in the hereinabove described device involving the substitution of substantial equivalents for the devices described are intended to be comprehended within the spirit of the present invention and that the invention is capable of extended application and is not confined to the exact showing of the drawing nor to the precise construction described and, therefore, such changes and modifications may be made therein as do not affect the spirit of the invention nor exceed the scope thereof as expressed in the appended claim.

What is claimed is:

40. In a typewriting machine, the combination with a revoluble platen having a circular flat knob fixed at one end thereof, of a resilient cover member removably fitted on the said knob, the said cover embracing the periphery of the knob and having inwardly directed end flanges disposed against the end faces of the knob, the exterior periphery of the cover being divided circumferentially and shaped to form an annular finger portion provided with transverse corrugations, and a smooth annular section having a diminishing taper toward the inner end of the knob and having circularly arranged consecutively numbered graduations designating uniformly spaced divisions of the circumference of the platen for indicating the relative position of a work sheet on the said platen.

ANNA M. LAROSE.
